GOLF PUTTER HEAD

Raymon W. Cook, San Antonio, Tex., assignor to Ray
Cook Golf Putters, Inc., San Antonio, Tex.

Filed Sept. 29, 1972, Ser. No. 293,526

Term of patent 14 years

Int. Cl. D21—02

U.S. Cl. D34—5 GH

FIG. 1 is a front elevational view of a golf putter head showing my new design.

FIG. 2 is a front end view of FIG. 1.

FIG. 3 is a top plan view of FIG. 1.

FIG. 4 is a rear elevational view of FIG. 1.

FIG. 5 is a vertical sectional view, taken on the line 5—5 of FIG. 4, looking in the direction of the arrows.

FIG. 6 is a bottom plan view of FIG. 1.

I claim:

The ornamental design for a golf putter head, as shown.
